UNITED STATES PATENT OFFICE.

FRED C. BERG, OF COALINGA, CALIFORNIA, ASSIGNEE TO ELI P. PLAUGHER, OF COALINGA, CALIFORNIA.

PUMP.

Application filed September 11, 1919. Serial No. 323,079.

To all whom it may concern:

Be it known that I, FRED C. BERG, a citizen of the United States, residing at Coalinga, in the county of Fresno and State of California, have invented certain new and useful Improvements in Pumps, of which the following is a specification.

This invention relates to pumps, and more especially to those having multiple cylinders with solid reciprocating pistons, and the object of the same is to produce an improved pump wherein the flow of liquid will be constant, when the device is in operation.

Another object of this invention is the production of a pump having a plurality of cylinders and operating mechanisms whereby the piston in each cylinder is simultaneously drawing liquid into one end of the cylinder while discharging liquid from the other end thereof, thus causing a constant flow of liquid from each cylinder when the pump is in use.

Other objects will appear in the following specification and claims.

In the drawings,

Figure 1 is a side elevation and

Figure 2 is a plan view of this pump, each partly in section.

Figures 3 and 4 are cross sections on the line 3-3 and 4-4 respectively of Figure 1.

Figure 5 is a horizontal section through the inlet end of one cylinder on an enlarged scale,

Figure 6 is a vertical section through the upper end of a well casing, and

Figure 7 a cross section on the line 7-7 of Figure 6.

By referring to the drawing it will be seen that 1 designates a well casing and 2 the barrel therein leading down into the water or other liquid to be raised. This barrel 2 extends a relatively short distance above the end of the well casing 1 and has its end threaded. A nipple 3 having the threaded flange 3' is mounted upon the threaded end of the barrel 2 as best shown in Figure 6. A valve seat 50 is carried in the nipple and has the guide 51 situated below the seat itself so as to form an eye to receive the stem 53 of the valve 52. A spring is provided for normally holding this upwardly opening valve 52 in a closed position. A pipe 4 leads upwardly from this valve to a T-coupling 5, whence it is branched as at 6 and 6' and each

branch leads through a valve 7 and 7' respectively and into the inlet end of cylinders 8 and 8' mounted on a frame work 9 and as seen in Figure 2, there are preferably two such cylinders.

The pipe 30 leads from T-joint 5 as shown in Figure 2 and is connected by a T-joint 30' with said short pipe 31 to the check valve 7". Elbows 31' lead from the check valve 7" and communicate with the interior of the lower end of the cylinders 8 through the cylinder heads 32.

Within each cylinder is a solid reciprocating piston 10, whose rod 11 leads out through the cylinder head thereof and connects with a block 12 slidably mounted in a guide 13 supported by a cross head 14. The blocks in turn are connected by pitman rods 15 with cranks 16 at opposite ends of a shaft 17 and the shaft is rotated in any appropriate manner as by a belt 18 passing around a pulley 19 which is fast on the shaft between its bearings. For this reason the pistons are reciprocated simultaneously and oppositely within the cylinders.

The flow or delivery pipe 24 is connected with a T-coupling 25 and branched as at 26 and each branch 26 is connected with a T-joint 33. Short pipes 34 lead from these T-joints 33 and are connected to the check valves 27 as shown in Figures 2 and 5. It should further be noted that short pipes 35 also lead from the T-joints 33 and are connected by elbows 36 to the elongated pipes 37. Elbows 38 are carried by the opposite ends of the pipes 37 and are connected to the check valves 39 from which extend elbows 40 communicating with the inner rear ends of the cylinders 8 through the cylinder heads 32.

When the device is in operation and the pistons 10 are reciprocated within the cylinders 8, it should be understood that there will be a continuous flow of liquid from each cylinder. For the purpose of explanation, attention is invited to Figure 2 wherein an arrow is disclosed indicating the direction of movement of one of the pistons. As this piston moves toward the right end of the cylinder it will be seen that liquid within this end of the cylinder will be forced therefrom passing through check valves 27, short pipes 36, T-joints 33 branch 34, T-joint 25 and thence through delivery pipe 24. At the same time this advance of the piston causes

liquid to be drawn from the barrel through the valve 3 to the T-joint 5 and thence through the pipe 30 and T-joint 30' to and through the T-joint 7" and elbow 21' into 5 the opposite or rear end of the cylinder.

As this piston starts on its return stroke, it is obvious that the liquid within the left end of the cylinder 8 will pass therefrom through elbow 40, check valve 39 and elbow 38 10 through pipe 37 and elbow 36 and thence through short pipe 35 elbow 33 and branch 26 and then to and through the delivery pipe 24. As this action is taking place it is obvious that the flow of liquid from T- 15 joint 5 will pass through branch 6 and valve 7 into the right end of cylinder 8. Although only the operation of one cylinder has been set forth, it is to be understood that the operation of the other cylinder 20 is exactly the same with the exception that as the one cylinder moves in one direction the remaining cylinder is moving in the opposite direction, although it is not absolutely necessary to have this particular form of 25 operation, for irrespective of whether or not the cylinder is moved in unison and in the same direction or in opposite directions liquid will be drawn into the end of each cylinder and discharged from the opposite 30 end thereof continuously, according to the direction of movement of the piston.

Therefore, it will be seen that a very efficient pump mechanism has been provided wherein each cylinder will produce a continuous pumping action drawing water into 35 one end and ejecting water from the opposite end thereof and then drawing water into the end from which water has been ejected and forcing water from the end 40 wherein it has just been drawn. The arrangement of the pipes, T-joints, elbows and valves is such as to allow a single feed to provide a feed for each end of the cylinder, while the arrangement also allows water to 45 be ejected from each end of each cylinder and finally directed into a single delivery pipe, it being obvious that as the water of the several pipes is finally passed into a single pipe, it will driven therethrough at 50 a very high pressure for any purpose desired.

In the present illustration of my invention it is presumed that the pumping cylinders are within the theoretical suction distance from the level in the well, or that the inherent gas pressure in the well will force the liquid in the well to a point where it 55 may be taken up by the pump.

The foregoing description and the drawings have reference to what may be considered the preferred, or approved form 60 of my invention. It is to be understood that I may make such changes in construction and arrangement and combination of parts, materials, dimensions, et cetera, as may 65 prove expedient and fall within the scope of the appended claims.

Having thus fully described my invention, what I claim as new and desire to secure by Letters Patent is:—

1. The combination with a pair of cylinders, solid pistons therein, and mechanism for reciprocating said pistons simultaneously and oppositely; of a well casing, a barrel therein extending a relatively short 75 distance above the well casing and having its upper end threaded, a nipple mounted upon the threaded end of the barrel, a valve seat situated in said nipple and on the end of the barrel, an upwardly opening check valve 80 situated within the nipple, a pipe leading from the nipple and branched into the heads of the two cylinders, inwardly opening check valves within said branches and flow pipes opening from said heads and containing upwardly opening check valves. 85

2. In combination, a wall casing, a barrel therein extending a relatively short distance above the wall casing and having its upper end threaded, a nipple mounted upon the 90 threaded end of the barrel, a valve seat situated in said nipple and on the end of the barrel, an upwardly opening check valve situated within the nipple, a pipe leading from the nipple and pumping mechanism 95 communicating with said pipe.

In testimony whereof I affix my signature in presence of two witnesses.

FRED C. BERG.
